UNITED STATES PATENT OFFICE

MAX KAHN, OF NEW YORK, N. Y., ASSIGNOR TO PEN-O-PENCIL CO., INC., OF NEW YORK, N. Y., A CORPORATION OF TENNESSEE

DESIGN FOR A COMBINED PENHOLDER AND DESK PAD

Application filed September 8, 1928. Serial No. 28,073. Term of patent 7 years.

To all whom it may concern:

Be it known that MAX KAHN, a citizen of the United States, and resident of New York city, in the county of New York and State of New York, has invented a new, original, and ornamental Design for a Combined Penholder and Desk Pad, of which the following is a specification, reference being had to the accompanying drawing, forming part thereof, in which the figure is a perspective view of a combined penholder and desk pad embodying my new design.

I claim:

The ornamental design for a combined pen holder and desk pad as shown.

Dated New York city, September 7th, 1928.

MAX KAHN.
